UNITED STATES PATENT OFFICE.

ROBERT Y. BARROWS, OF RUTHERFORD, AND GEORGE V. STRAHAN, OF NEWARK, NEW JERSEY, ASSIGNORS TO THE MITCHELL VANCE COMPANY, OF NEW YORK, N. Y., A CORPORATION OF NEW YORK.

DESIGN FOR A CENTER PLATE FOR A CHANDELIER-BODY.

50,169.

Specification for Design.

Patented Jan. 16, 1917.

Application filed December 2, 1916. Serial No. 134,773. Term of patent 7 years.

To all whom it may concern:

Be it known that we, ROBERT Y. BARROWS, a citizen of the United States of America, residing in the town of Rutherford, in the county of Bergen and State of New Jersey, and GEORGE V. STRAHAN, a citizen of the United States of America, residing in the city of Newark, in the county of Essex and State of New Jersey, have invented a new, original, and ornamental Design for a Center Plate for a Chandelier-Body, of which the

following description, in connection with the accompanying drawing, is a specification.

The single figure of the drawing is a plan of a center plate for a chandelier body, showing our new design.

We claim as our invention:

The ornamental design for a center plate for a chandelier body, as shown.

ROBERT Y. BARROWS.
GEORGE V. STRAHAN.
